UNITED STATES PATENT OFFICE.

KAREL VESELY, OF TYNICE, NEAR SAZAVOU, CZECHOSLOVAKIA.

SEWING-MACHINE.

1,339,243.

Specification of Letters Patent.

Patented May 4, 1920.

Application filed July 10, 1919. Serial No. 309,913.

To all whom it may concern:

Be it known that I, KAREL VESELY, a citizen of the Czechoslovak Republic, and residing at Tynice, near Sazavou, Czechoslovakia, have invented certain new and useful Improvements in Sewing-Machines, of which the following is a specification.

The present invention has reference to certain new and useful improvements in sewing machines and relates more particularly to double lock stitch machines, and its object is to simplify and improve the construction and operation of machines of this type, which is accomplished by arranging 10 the shuttle unit above the work plate within a case secured to the presser foot bar and by positioning the needle bar with its actuating mechanism below the work plate and imparting to the needle bar a peculiar 15 pendulum or rocking movement, which permits the needle to cast the needle loop caught by the shuttle point in the manner requisite for forming the double lock stitch.

In order to make my invention more readily understood I will now describe it in connection with the accompanying, more or less diagrammatic drawings, in which Figure 1 is a side elevation and Fig. 2 a rear view, both partly in section.

30 The shuttle of the shape shown and denoted by the reference numeral 1 is housed within the cup-shaped case 2 secured to the cranked-out presser foot bar 3. The case as well as the shuttle are relatively stationary arranged on the presser bar. The driving shaft 5 is journaled in the frame bearing 6 and 7 denotes the frame portion in which a pin 8 is adjustably secured and supported. To the driving shaft 5 is keyed 35 a crank arm 11 whose pin 12 is pivotally secured to the rigid frame 12', 13', 14'. The pin 13 is linked to a connecting rod 15, the other end of which is pivotally secured to the machine frame, as at 10. The pin 12 moves through a complete circle, as indicated by a dotted line in Fig. 2, in the direction of the arrow *a*. To the pin 13 is 40 imparted a reciprocation in the arc of a circle *d*, which causes the pin 14 to execute the closed double-loop curve 16 with one node, the direction of travel being indicated by arrow *b*. The pin 14 is fulcrumed on the needle bar 17, which latter is guided in sleeves 18 and 19. These guide sleeves form 45 part of a bracket arm 20 (Fig. 1) which

is rockingly suspended by the shaft 21 journaled in the plane of the needle plate of the machine. The needle bar, thus, is forced to join in the rocking movement of the arm 20, so that the needle always traverses the 60 needle plate and the work at one and the same point, the stitch forming point, the needle point in each cycle moving through the treble-loop curve 23 (Fig. 2) having two nodal points, the lower one of which coincides with the stitch forming point.

The operation of the described mechanisms is the following:—The needle pierces the work in vertical direction, ascends toward the left as indicated by the arrow *c* 70 to the highest point of its travel, next recedes slightly which forms the needle loop, and then moves over toward the right. The loop is now caught-up by the point of the shuttle 1, is then looped around and down 75 the shuttle by the needle in its further descent, which completes the double lockstitch formation.

The needle thread 28 passes from the bobbin over a tension member 24, through the 80 eye 25 on the needle bar, then through the eye 26 on the rock arm 20, thence through eye 27 on the needle bar, and finally up the latter to the needle eye. Thus, the thread is tensioned or taken up only after the 85 needle has dropped below the stitch plate.

The work is fed forward in well known manner by means of the feeder plate or dog 22 secured to the feed bar 29, the one end of which is guided on a cross-pin 30, and 90 whose other end is pivotally connected by means of a pin 31 journaled in the fixed frame bearing 32 (Fig. 1) to the connecting rod 33. This latter rigidly extends from an eccentric 34 driven by the main driving 95 shaft 5 and rocks about the fulcrum pin 8, which can be adjusted within that portion of the machine frame 7 and slot 7' in the connecting rod 33 and said pin can be locked in the desired fulcrum position; the extent 100 of the stitches can therefore be readily altered thereby.

What I claim is:—

1. In a sewing machine, in combination with the machine frame including the work 105 plate, stitch forming mechanism, comprising a presser bar, a case near the lower extremity thereof, a shuttle in said case, said parts all arranged above said work plate, and a needle actuating mechanism arranged 110

below said work plate, the needle reciprocating through said work plate in timed co-operation with said shuttle.

2. In a sewing machine, in combination with the machine frame including a work plate, shuttle means arranged above said work plate, and needle actuating means below said work plate, comprising actuating mechanism for reciprocating the needle in co-operation with said shuttle means, and for rocking it simultaneously in such manner that its point moves through a compound curve having two nodal points, the one of which coincides with the stitch forming point.

3. In a sewing machine, in combination with the machine frame including the main drive and a work plate, a presser bar, a shuttle unit thereon; a needle actuating mechanism located below said work plate and comprising a needle bar, a needle in the upper end thereof adapted to co-operate with said shuttle unit, a bracket member rockingly journaled at its upper end in the plane of said work plate, guide sleeves extending from said bracket member and designed to slidably receive said needle bar, a triangular frame, one apex of which is fulcrumed on said needle bar intermediate said guide sleeves, a crank arm operated through said main drive and jointed to the second apex of said triangular frame, and a link respec-

tively pivoted to the third apex of said triangular frame and the machine frame, the parts being so constructed and co-operating that on rotation of the main driving shaft the triangular frame is rockingly actuated in such manner that the needle point for each complete stitch forming cycle passes through a treble-loop curve with two nodal points, the lower node coinciding with the stitch forming point in the work plane.

4. In a sewing machine, in combination with the machine frame including a work plate, a shuttle unit above said work plate, a needle and needle bar below said work plate, actuating mechanism therefor imparting to the needle bar a rocking movement, which causes it to execute a closed double-loop curve with one node, and take-up means for drawing-up the needle thread only after the needle has descended below said work plate, comprising three thread eyes, two of which are located on said needle bar and the third on said bracket member, the thread being guided first through one of said needle bar eyes, then through the bracket member eye, and finally through the second needle bar eye.

KAREL VESELÝ.
